FIG. 2

FIG. 3

FIG. 4

FIG. 5

FIG. 6

FIG. 7

FIG. 8

FIG. 1 is an isometric view, on an enlarged scale, of a bird feeding station according to one embodiment of the invention and illustrating the new design;

FIG. 2 is an elevational view of either end thereof;

FIG. 3 is a bottom plan view thereof;

FIG. 4 is an elevational view of either side thereof;

FIG. 5 is a top plan view thereof;

FIG. 6 is an elevational view of either end of a modified design;

FIG. 7 is a bottom plan view thereof; and

FIG. 8 is an elevational view of either side thereof.

The appearance in top plan of the embodiment illustrated in FIGS. 6, 7 and 8 is the same as that illustrated in FIG. 5.

The dominant characteristics of the design are illustrated in full lines, and in some of the drawing views certain broken line portions, shown for illustrative purposes only, have been omitted for ease of illustration.

I claim:

The ornamental design for a bird feeding station, as shown and described.
